UNITED STATES PATENT OFFICE

MAURICE E. SHAW, OF LOS ANGELES, CALIFORNIA

EASY LIFT SANITARY FLOWER CONTAINER

Application filed June 24, 1931. Serial No. 546,517.

An object of this invention is to provide a novel and more satisfactory flower container for use in cemeteries.

A defect found in producing flower containers, is that when the flowers are removed the container lays idle and the mud and snails collect in and on top of the container, making it necessary for the person to first clean the container before putting flowers in it.

10 To overcome this difficulty I have provided a receptacle having a beaded edge at its top and bottom ends, an open top and closed bottom that when placed in the casing in one position acts as a holder for flowers and when reversed is locked to the casing to prevent water from raising the receptacle and keeps it below the surface of the ground so that it could not be cut off by a lawn-mower.

20 A feature of the invention is the beaded ends extending inwardly at each end of the receptacle to permit easy access of a person's fingers to grasp and easily lift the receptacle out of the casing.

25 An advantage of the invention is a novel method of locking the receptacle to the casing when in reversed position.

Another object of this invention is to so construct the bottom of the receptacle a certain distance from its bottom edge between two beads and pressing the beads against the bottom piece to form a complete edge on each side to prevent the bottom from being knocked out.

35 Other objects are simplicity and cheapness of construction.

Other objects, advantages and features of invention may appear from the accompanying drawing, the subjoined detailed description and the appended claims.

40 The accompanying drawing illustrates the invention.

Figure 1 is an axial section of a specimen of the newly invented flower container in position in the ground showing the receptacle

being lifted out of the casing by a person's fingers a fragment of which is shown.

Fig. 2 is a plan view of Fig. 3.

Fig. 3 is a view analogous to Fig. 1 showing the receptacle in reversed position and being broken away in sections to show interior construction and method of locking same to the casing.

Fig. 4 is a section on line 4, Fig. 1.

Fig. 5 is a plan view looking down on the top of the receptacle showing the position of the two lock beads.

Fig. 6 is an enlarged fragmental sectional detail showing the construction of the bottom piece to form the closed bottom of the receptacle.

Fig. 7, is an enlarged fragmental side elevational detail showing one of the locking beads.

Fig. 8 is a face view of Fig. 7.

The invention comprises a casing 1 and a receptacle 2 that may be made out of galvanized or any suitable metal.

As shown in Fig. 1 the casing 1 is shown placed in the ground 3 and having at its top 75 an outwardly extended bead 4 and at a distance from the bottom the inwardly extended beads 5 and 6 that are spaced apart as shown.

The receptacle 2 is provided at its ends 75 with inwardly extended beads 7 and 8 that are so constructed that a person's fingers may grasp and lift the receptacle easily out of the casing.

9 indicates a bottom piece that is inserted 80 between the inwardly extending beads 10, 11 and that are pressed against the bottom piece to form a complete edge on each side to prevent the bottom from being knocked out by any pushing against it as is the general 85 practice by persons using the container.

At the top end of the receptacle 2 are outwardly extending circular beads 12 and 13 that when the receptacle 2 is reversed the beads 12, 13 fit between the beads 5 and 6 90

to lock the receptacle to the casing as shown in Fig. 3 of the drawing.

When the receptacle 2 is in this position it is shown slightly below the surface of the ground and any water that may fall on it from rain or other sources will drain through the holes 14 and flow around the sides but cannot raise the receptacle above the surface of the ground.

10 14a indicates a seam construction of the container.

In operation when the flowers are removed from the container the receptacle 2 is easily raised from the casing 1 by the fingers 15 of a person grasping the bead 7 as shown in Fig. 1.

15 The receptacle is then reversed and locked to the casing as shown in Fig. 3 thus preventing any water from raising it above the surface of the ground so that the receptacle could not be cut away by a lawn mower.

20 To raise the receptacle from this reversed position to again fill with flowers the person's fingers grasp the bead 7 to easily lift 25 it from the casing.

I claim:—

1. A flower container comprising an outer casing provided at its top with an outwardly extending bead and at its bottom with two inwardly extending beads spaced apart and an inner receptacle having an open top and a closed bottom; said receptacle provided at its ends with inwardly extended beaded edges and means to lock the receptacle to the casing.

30 2. In a flower container comprising an outer casing provided at its top with an outwardly extending bead and at its bottom with two inwardly extending beads spaced apart; a receptacle within said casing having an open top and a closed bottom; a lock near the top of said receptacle and when the receptacle is reversed prevents the water from raising said receptacle above the top of said casing.

35 3. A flower container comprising an outer casing provided at its top with an outwardly extending bead and at a certain distance from its bottom end with two inwardly extending beads spaced apart; an inner receptacle having at its ends inwardly extended beaded edges to permit a person's fingers to grasp and lift said receptacle easily out of said casing; a bottom piece inserted between two beads a certain distance from the bottom of 50 said receptacle; said beads being pressed against said bottom piece to form a complete edge on each side to prevent the bottom from being knocked out and a lock at the top of said receptacle that fits into the space between said inwardly extending beads of the casing when said receptacle is in reversed 55 position to lock it.

4. A flower container to be placed in the ground comprising an outer casing and a receptacle to fit into said casing having an

open top and a closed bottom; said receptacle provided at its ends with inwardly extended beaded edges and provided with a plurality of holes equally spaced around the periphery underneath said bottom to drain water when said receptacle is in reversed position.

In testimony whereof, I have hereunto set my hand at Los Angeles, California, this 12th day of June, 1931.
